UNITED STATES PATENT OFFICE.

WILLIAM H. GOSS, OF FRANKLIN TOWNSHIP, SOMERSET COUNTY, NEW JERSEY.

GAS-GENERATING BURNER.

Application filed February 7, 1922. Serial No. 534,661.

To all whom it may concern:

Be it known that I, WILLIAM H. Goss, a citizen of the United States, residing at Franklin Township, in the county of Somerset and State of New Jersey, have invented certain new and useful Improvements in Gas-Generating Burners, of which the following is a specification.

This invention has reference to a burner 10 for generating gas for heating and lighting purposes.

An important object of the invention is to provide a gas-generating burner in the form of an attachment for stoves, furnaces 15 or other heat providing agencies, whereby the use of coal and wood for fuel is dispensed with, the required heat being supplied by the ignition of the gas generated by the burner.

20 Another object of the invention is to provide a burner for kerosene oil in which the said oil is superheated by the flame of the burner for generation into gas, means being provided for receiving and collecting the 25 vaporized gases passing beyond the burner-jets whereby they may be stored for lighting purposes or for return to the burner jets.

An additional object is to provide a gas 30 generating burner of generally improved construction and design and embodying novel means for the removal of carbon deposit from the burner pipes without requiring the taking apart of the burner.

35 Various other objects and advantages of the invention will become apparent during the following description.

In the drawings,

40 Figure 1 is a front elevation of a furnace with the burner attachment applied thereto.

Figure 2 is a vertical central section thru the lower end of the furnace, showing an end view of the burner.

45 Figure 3 is a section on line 3-3 of Figure 2 which shows the burner in side elevation.

Figure 4 is a horizontal cross section thru the furnace showing the burner in top plan.

50 Figure 5 is a section thru the ash-pit of the furnace disclosing the burner supply pipe and feed-pipe.

Figure 6 is longitudinal section thru one of the burner-jets showing the needle valve.

55 Figure 7 is a longitudinal sectional view

thru one of the generating pipes of the burner disclosing the carbon collector therein.

Figure 8 is a vertical cross section thru the said pipe and collector showing the various gas channels.

Figure 9 is a view in perspective of one of the flame-spreaders, and

Figure 10 is a perspective view of a shield for the front end of the burner.

Describing the invention in detail, 10 designates a furnace to which the invention is applied, the latter having the generating burner overlying the grate bar 11 and supplied with kerosene oil from a supply tank 12. This tank is suitably supported at a convenient distance from the furnace and is connected to the burner by a pipe-line 13 which penetrates the ash-pit of the furnace in the manner shown. A second pipe-line 14 also penetrates the ash pit and connects with a storage tank 15. Each pipe-line is curved, as at 16, in the arc of a circle the center of which coincides with the hinge of the ash-pit door 17 thru one of the draft 80 openings of which the said pipe extends. Hence, the door may swing outwardly along the curved portions of the pipes when opened.

The generating burner comprises a plurality of horizontal pipes or tubes 18 arranged in spaced parallel relation with their opposite ends closed by plugs 19. These tubes are connected, one to the other, at relatively opposite ends to provide alternating loops in which the kerosene is heated. The kerosene is conducted to the inlet end 20 of the generating loops thru a pipe 21 which extends inwardly toward the center of the burner, as shown in Figure 4, and connects with a vertical pipe 22. Pipe 22 extends downwardly thru the grate and is coupled to pipe line 13 as shown in Figure 3. The burner or flame pipe 23 of the device is arranged crosswise of generating tubes 18 and below the same, being connected by horizontal 24 and vertical pipe 25 to the outlet end 26 of the tubes. The opposite end of the flame pipe is coupled by a horizontal pipe 27 and a vertical pipe 28 with a branch pipe 29. The branch pipe extends crosswise of the front end of the burner and connects with one end of a longitudinally disposed reserve pipe 30. To the opposite end of pipe 30 is connected an out-

let pipe 31, similar to member 21 and coupled to pipe line 16 as shown in Figures 2 and 3.

In using the burner the oil from tank 12 is conducted thru the various tubes of the burner and is ignited above jets 32 of the burner pipe 23, at which points the oil mixes with air entering thru the ash pit and open grate of the furnace. As the kerosene passes thru tubes 18 on its way to jets 32 it is heated and converted into gas by the burning gases below the tubes and hence readily mixes with air at the valves when sprayed in vaporized or gaseous form from the jet. Any surplus gas passing beyond the jets is conducted thru pipe line 16 to the gas storage tank 15 where it accumulates under pressure. As this tank is in communication with the burner pipe the reserved gases are free to return under back pressure to the jets, consequently, insuring a steady feed thru the flame jets. The ignition of the air and gas mixture causes a flame above each jet and since tubes 18 pass thru the flames it will be seen that the oil is preheated and converted into gas before reaching the jets.

Each jet has a needle-valve 33 for regulating the flow of gas thru the burner pipe. The valve is enclosed in a casing 34 and projects into the ash pit of the furnace, as shown in Figures 2 and 3, so that handle 35 may be conveniently reached for making adjustments. To start the burner gas may be forced thru jets 32 for ignition by means of pump 36 which expels the gases from the tank. To the tank may be connected a distributing line 37 having a regulating valve 38. The gas supplied thru line 37 may be used for illumination or other purposes. The tank may be drained thru a drain-cock 39.

Straddling tubes 18 is a removable bracket 40 having clips 41 at opposite ends for gripping certain of the tubes and flame spreading discs 42 are swiveled at 43 of the bracket for tilting movement. The discs are above the tubes and permit deflection of the flames in the desired direction.

Figures 7 and 8 show the interior construction of the burner tubes which are provided, in the present instance with a longitudinally extending core 44 of polygonal cross section and terminating at one end with a hook 45. This core fits snugly within the tube and its sides define a series of gas channels 46 as shown in Figure 8. One of these channels is located along the bottom of the tube against which the flame impinges. It is along the bottom of the tube that the heavier deposits of carbon are formed in the usual type of burner which are difficult to clean without taking them apart. The provision of a passage at this point thru which the gas is free to flow prevents the accumulation of carbon de-

posits on the pipes, such deposits accumulating on the core which is removable and hence readily cleaned. To remove the core the plug 19 at one end of the tube is unscrewed, exposing hook 45 of the core which can then be easily withdrawn.

To provide for an intimate mixture of air and gas the burner is preferably mounted upon a suitable base 47 of fire brick or other plastic material. The base may be in one piece or in sections as shown in Figure 4 and completely covers grate bar 11 of the furnace with the exception of the central portion thru which the needle-valve and supply pipe extend, a central opening 48 being provided in the base as shown to provide an air passage for conducting and concentrating the draft from the ash-pit around the flame jets of the burner. The suction of the draft causes the gas to mix readily with air and to ignite above the jets. The base is of such a height as to bring the burner on a level with the fire door 49 of the furnace and a supporting plate or shield 50 is fastened to the burner for supporting the same so that the plug can be conveniently unscrewed when door 49 is opened to clean the burner. This plate is suitably perforated as at 51 to receive the forward ends of tubes 18 and provides an air shield for the front of the burner.

This gas-generating device may be applied in other ways than as here described and provides gas generating means of an economical character which is useful for both heating and lighting. The kerosene is supplied in liquid form from one container and is stored, in gaseous form, in a dispensing container from which it may be returned to the heating burner or used for illuminating as above described.

From the foregoing it is believed that the novel features of the invention, as well as the construction and operation thereof, will be understood without further detailed description.

What is claimed is:

1. A gas-generating device including a burner having generating tubes, plugs closing the opposite ends of the tubes and removable therefrom, and a removable core or filler for each tube, said core comprising a solid rod of polygonal cross section having a catch-hook at one end and flat sides defining separate gas passages along the inside of the tube, one of which is disposed adjacent the flame-impinging side of the tube.

2. A gas-generating device including a burner having a flame tube and generating tubes above the flame tube to be heated by the flame of the latter, a centrally perforated base for supporting the burner or a furnace grate, means for supplying oil to

- the generating tubes for conversion into gas by the flame, means for conducting the gas thru the flame pipes for consumption therein, means for conveying any surplus gas 5 from the burner to a place of storage, and valve means for regulating the feed of the gas thru the flame tubes, said valve means projecting below the grate of the furnace.
3. A gas generating burner for use in a 10 furnace, comprising a centrally apertured base of plastic material adapted to overlie and completely cover the grate of the furnace with the exception of the central portion, a burner mounted on said base and 15 supported by the latter on a level with the fire door of the furnace, a perforated plate
- engaging the loops of the burner providing an air shield for the burner, and a pair of independent pipe lines penetrating the ash pit of the furnace from the outside of 20 the latter and connecting with the said burner through the said central opening in the said base, one of said pipe lines being an oil-supply line and connecting with the inlet end of the burner, and the other pipe 25 line being an oil preserve line and connecting with the outlet end of the burner for collecting any surplus gas passing beyond the jets of the burner.

In testimony whereof I affix my signature. 30

WILLIAM H. GOSS.
